CHILD'S CHAIR

John Roger Gunderson, Homestead, Fla.

Application November 19, 1958, Serial No. 53,445

Term of patent 14 years

(Cl. D15—1)

Fig. 1 is a front elevational view of a child's chair, showing my new design;

Fig. 2 is a top plan view of the chair shown in Fig. 1;

Fig. 3 is a back elevational view of the chair shown in Fig. 1; and

Fig. 4 is an elevational view showing the left side of the chair shown in Fig. 1.

I claim:

The ornamental design for a child's chair, substantially as shown.
